(57) **CLAIM**

The ornamental design for a sleeping bag, as shown and described.

DESCRIPTION

FIG. 1 is a front side perspective view of our sleeping bag, shown in the fully closed configuration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front side perspective view of our sleeping bag, shown in the fully open configuration;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines, shown throughout the views on the surface of the sleeping bag, represent stitching, which forms no part of the claimed design.
